CENTRIFUGAL FAN CASING

Kenton D. McMahan, Schenectady, N. Y., assignor to General Electric Company, a corporation of New York

Application June 24, 1938, Serial No. 215,643

1 Claim. (Cl. 230—47)

The present invention relates to centrifugal fan casings of the type having a plurality of outlets, and to portable electric tools equipped with such casings for motor ventilating and cooling purposes.

The object of my invention is to provide an improved construction and arrangement in fan casings of this type and in portable electric tools equipped with such casings, and for a consideration of what I believe to be novel and my invention, attention is directed to the accompanying description and the claim appended thereto.

In the accompanying drawing, Figure 1 is a side elevation of a portable electric motor driven tool having fan casing embodying my invention; Fig. 2 is a sectional view taken on line 2—2 of Fig. 1, and Fig. 3 is a sectional view taken on line 3—3 of Fig. 2.

Referring to the drawing, there is shown a portable electric motor driven tool comprising an electric motor 1 having a handle 2 at one end and a driving head 3 at the other end. The driving head is equipped with a suitable chuck 4 for holding drills and the like. The driving connection between the motor and the chuck is carried within the head 3.

Between the driving head 3 and the electric motor is a bladed centrifugal fan 5 keyed to the motor shaft 6. The fan has an inlet 7 at the center. Upon rotation, air is drawn into the motor casing through inlet openings 8 and through the motor casing to the fan inlet 7. The air is discharged from the fan to a casing which has end walls comprising the end wall 9 of the driving head 3 and the end frame 10 of the motor and which has peripheral walls comprising an intermediate member 11 which is clamped therebetween. As shown in Fig. 2, the member 11 is of substantially square section. It has an inwardly extending flange 12 provided with a circular opening 13 which fits over and is seated on a circular boss 14 on the wall 9 of the driving head 3 so that the flange 12 is substantially flush with the wall 9. Integral with and extending along the edges of a flange are walls 15 which project axially therefrom over the fan and bridge the space between the driving head 3 and the motor to provide the outer periphery of the fan casing. The inner ends of the walls 15 terminate

in cutoffs 16. The front faces 17 of the walls 15 extend from the cutoffs to the outside of the casing and serve to direct air from the fan to discharge outlets 18 arranged in the corners of the fan casing. The inner surfaces 19 of the walls 15 extend spirally beyond the cutoff in the direction of rotation of the fan and overlap the faces 17 of the succeeding walls 15 to define the other sides of the discharge outlets. The inner surfaces 19 diverge from the periphery of the fan and provide passages increasing in area from the cutoff around the fan toward the outlets.

From one aspect, it is seen that the discharge passages for the fan are provided by spirally arranged walls having their inner ends terminating in cutoffs 16 and extending therefrom along the sides of the fan casing in the direction of rotation of the fan and having the other ends overlapping the succeeding walls to provide the discharge outlets. The front faces 17 of the walls are also spirally arranged, providing a gradual increase in area of the discharge passages and a gradual change in direction of the discharge of air. Due to the shape of the discharge passages it is substantially impossible to damage the fan by inserting a screw driver or similar device in the discharge outlets. This eliminates the need for guards. The casing is particularly suited for portable electric motor driven tools in that the outlet passages do not project materially beyond the motor and guards for the passages are not required.

What I claim as new and desire to secure by Letters Patent of the United States is:

In a centrifugal fan, a fan casing having a square outer surface, outlets at the corners thereof, cutoffs within the casing, walls extending from in front of the cutoffs as regards the direction of rotation of the fan and terminating at the outer surface of the casing for directing air to the adjacent outlets, and walls extending from the cutoffs beyond the cutoffs as regards the direction of rotation of the fan and diverging from said first walls and terminating at the outer surface of the casing providing passages increasing in area in the direction of rotation toward the succeeding outlets.

KENTON D. McMAHAN.
